JOSEPH BAMPFORD AND CYRIL JOSEPH BAMPFORD, OF UTOXETER, ENGLAND

POTATO OR LIKE DIGGER

Application filed July 19, 1928, Serial No. 294,020, and in Great Britain July 27, 1927.

This invention relates to machines for digging potatoes or the like and refers more particularly to that type of machine having a share or its equivalent behind which is a rotary digging element comprising forks or tines mounted on a transversely disposed rotary disc or head or its equivalent in combination with a second or receiving rotary disc or grid.

10 The object of the present invention is to provide a generally improved construction of such machines.

One of the features of the present invention is to employ in combination a rotary digging element comprising forks or tines mounted upon a transversely disposed rotary disc or head or its equivalent arranged on a substantially horizontal axis and a rotary receiving disc or screen arranged on a vertical 20 or inclined shaft and disposed at the side of the digging element.

A further feature of the present invention is to make provision so that the receiving disc or screen can be adjusted in a direction parallel to the longitudinal axis of the machine.

25 A further feature of the present invention is to mount the shaft of the receiving disc or screen so that it can be swung or adjusted laterally with respect to the longitudinal axis of the machine.

30 Referring to the drawings:—

Figure 1 is a plan view of the machine.

Figure 2 is an end view.

35 Figure 3 is a plan view upon an enlarged scale showing the driving means for the shaft of the receiving member.

Figure 4 is a view in side elevation of the apparatus shown in Figure 3.

40 Figure 5 is an end view of the apparatus shown in Figure 3.

Figure 6 is a side view of another arrangement of gearing and screen.

Figure 7 is an end view thereof.

45 In the construction illustrated the machine comprises a suitable frame 1 supported upon an axle 2 having supporting wheels 3.

The machine is provided with a main driving shaft 4 which is arranged substantially centrally and longitudinally with respect to 50 the machine, and this shaft receives motion

through suitable gearing from the supporting wheels.

Mounted between the supporting wheels is a share 5 for raising the ridge containing the crop, and to the rear of this share is a digging element which consists of a rotary disc or member 6 mounted upon the main driving shaft 4 and fitted with hingedly attached forks or tines 8, this member being disposed transversely with respect to the longitudinal centre line of the machine and being mounted upon a substantially horizontal axis.

The forks or tines 8 are mounted in tine carriers 7 and these tine carriers are connected by arms 26 to a reel 27 rotatably mounted upon an arm 30 carried by an arm 28 extending over the disc 6 and carried by the main frame. The reel 27 is thus mounted eccentrically in relation to the rotary disc or member 6. The arms 26 serve to locate the tines 8 in suitable digging positions.

At the side of this rotary digging element is a countershaft 9 which is parallel to the main driving shaft and which is driven by means of sprockets 10 and 11 and chain 12 or by other suitable means from the main driving shaft.

This countershaft 9 is supported in a U-shaped bracket 13 fixed to the frame and the countershaft carries a bevel wheel 14 which may be adjusted to and fro along the shaft. Alternatively, the countershaft may have a universal joint so that the shaft carrying the bevel wheel can be adjusted to any angle.

Gearing with this bevel wheel 14 is a bevel pinion 15 fixed on a shaft 16 which is connected by a universal joint 17 to a shaft 18. This shaft 18 extends downwardly and is supported in a bearing 19. The bearing 19 has a projecting stud 20 which engages in an arcuate slot 21 in a bracket 31 struck from the centre of the countershaft 9 so that the shaft 18 can be swung laterally on either side of the vertical position and secured in any required position by a nut 22 on the stud 20.

At the lower part of this shaft 18 is fixed the rotary receiving element 23 which, in the construction illustrated consists of a disc 24 having tines 25 forming a bell shaped screen. Other forms of receiving element

may be substituted. The tines 25 extend downwardly and forwardly in spiral formation and are curved outwardly from their point of attachment to the said disc so that the diameter of the circle enclosing the free ends of these tines is larger than the diameter of the disc to which they are fixed.

The receiving element 23 is near the ground and is driven preferably in an anti-clockwise direction (when viewed from above), the arrangement being such that the crop, which is moved laterally with respect to the machine by the digging elements 8, is received upon this rotary receiving element 23 which checks its movement and causes it to be delivered at the side of the machine.

If required, the bevel wheel 14, bevel pinion 15, and shaft 16 may be movable bodily by sliding the bevel wheel along the countershaft 9. In such an arrangement the bracket 13 will be slotted and the bracket 31 will be moved along in relation to the bracket 13 and secured in a fresh position thereon.

In the construction shown the shaft 16 is provided with a bearing 29 in the bracket 13, but if the two bevel wheels 14 and 15 are to be adjustable in a direction parallel to the shaft 9 then the bearing 29 will be formed upon the bracket 31 instead of forming it upon the bracket 13.

Instead of thus providing for the bodily fore and aft adjustment of the receiving member and its shaft the receiving member 35 and its shaft may be swung in a fore and aft direction instead of providing for a swinging movement in a transverse direction. In such an arrangement the position of the bracket 31 is altered so that the depending portion occupies a position at right angles to that shown in the drawings.

In the construction shown in Figure 6 and 7 the universal joint 17 is omitted. In this arrangement the shaft 9 is supported in two bearings 32 and a swinging bracket 33 is provided for carrying the shaft 18. The shaft 18 is provided with a bevel wheel 15 gearing with the bevel 14 on the shaft 9.

The bracket 33 is connected to the webs 34 of the brackets 32 by means of bolts 35 passing through slots 36 so that the angle of the shaft 18 may be adjusted as required.

In any of these arrangements means are provided for retaining the shaft which carries the receiving element in any adjusted position, it being understood that this shaft can either move bodily, forwardly, or to the rear or can swing laterally through a suitable angle.

Upon the outer side of the receiving element or adjacent thereto we may provide a guard of netting or wood or sheet metal or other suitable material. This guard is mounted upon suitable supports which are

carried by brackets fixed on the frame of the machine.

It is to be understood that we do not confine ourselves to the type of rotary digging element shown and we may use any type of rotary digging element provided it is mounted upon a substantially horizontal axis.

What we claim then is:—

1. A potato digging machine comprising in combination a frame, an axle on said frame, supporting wheels on said axle, a main driving shaft, a share for raising the ridge containing the crop, a rotary digging element at the rear of the share, said digging element being arranged with its axis substantially horizontal and comprising a number of hingedly attached tines, a rotary element mounted eccentrically of said digging element, connecting arms from said rotary element to the hinged tines, said arms serving to locate said tines in suitable digging positions, a depending shaft disposed at the side of the digging element, a disc on said depending shaft, downwardly depending tines extending outwardly and forwardly from the periphery of said disc and adapted to form a bell shaped receiving screen, and means for driving the digging and receiving elements. 95

2. A potato digging machine comprising in combination a frame, an axle on said frame, supporting wheels on said axle, a main driving shaft, a share for raising the ridge containing the crop, a rotary digging element at the rear of the share, said digging element being arranged with its axis substantially horizontal and comprising a number of hingedly attached tines, a rotary element mounted eccentrically of said digging element, connecting arms from said rotary element to the hinged tines, said arms serving to locate said tines in suitable digging positions, a depending shaft disposed at the side of the digging element, a disc on said depending shaft, tines on said disc, said tines extending downwardly and forwardly in spiral formation and being curved outwardly from their point of attachment to said disc, so that the diameter of the circle enclosing the free ends of said tines is larger than the diameter of the disc to which the other ends of the tines are fixed, the planes enclosing said circle and said disc being in spaced relationship and means for driving the digging and receiving elements. 100

3. A potato digging machine comprising in combination a frame, an axle on said frame, supporting wheels on said axle, a main driving shaft, a share for raising the ridge containing the crop, a rotary digging element at the rear of the share, said digging element being arranged with its axis substantially horizontal and comprising a number of hingedly attached tines, a rotary ele- 115

ment mounted eccentrically of said digging element, connecting arms from said rotary element to the hinged tines, said arms serving to locate said tines in suitable digging positions, a **U** shaped bracket mounted parallel with and at the side of said main shaft, a counter shaft mounted in said bracket, means for driving said counter shaft from said main shaft, a bearing in said bracket, 10 a universal joint, one part of which is rotatably mounted in said bearing, driving means from said counter shaft to the said rotatable part of said universal joint, a depending shaft associated with the other part of 15 said universal joint, a bell shaped receiving screen on said depending shaft, said receiving screen comprising a number of tines rigidly fixed to a circular disc, said tines extending downwardly and forwardly in 20 spiral formation and being curved outwardly from their point of attachment to said disc, so that the diameter of the circle enclosing the free ends of said tines is larger than the diameter of the disc, to which the 25 other ends of the tines are fixed, the planes enclosing said circle and said disc being in spaced relationship and means for driving the digging and receiving elements.

4. A potato digging machine comprising in combination a frame, an axle on said frame, supporting wheels on said axle, a main driving shaft, a share for raising the ridge containing the crop, a rotary digging element at the rear of the share, said digging 30 element being arranged with its axis substantially horizontal and comprising a number of hingedly attached tines, a rotary element mounted eccentrically of said digging element, connecting arms from said rotary 35 element to the hinged tines, said arms serving to locate said tines in suitable digging positions, a **U** shaped bracket mounted parallel with and at the side of said main shaft, a counter shaft mounted in said bracket, a 40 chain drive from said main shaft to said counter shaft, a depending shaft disposed adjacent said counter shaft, bevel gears for driving said depending shaft from said counter shaft, a universal joint associated 45 with said depending shaft to provide means whereby said depending shaft can be swung about its upper end while being driven, a bracket fixed to said **U** shaped bracket and having an arcuate slot, a bearing in which 50 said depending shaft is adapted to revolve, a screw threaded stud associated with said bearing, said stud being adapted to engage said arcuate slot whereby said depending shaft can be locked in any adjusted position, 55 a disc on said depending shaft, tines on said disc, said tines extending downwardly and forwardly in spiral formation and being curved outwardly from their point of attachment to said disc so that the diameter of the 60 disc enclosing the free ends of said tines

is larger than the diameter of the disc to which the other ends of the tines are fixed, the planes enclosing said circle and said disc being in spaced relationship and means for driving the digging elements.

In witness whereof we affix our signatures. 70
JOSEPH BAMFORD.
